(57) **CLAIM**

The ornamental design for a mounting assembly, as shown and described.

DESCRIPTION

FIG. 1 is a front elevational view of a mounting assembly showing an embodiment of my new design.

FIG. 2 is a rear elevational view thereof.

FIG. 3 is a left side elevational view thereof.

FIG. 4 is a right side elevational view thereof.

FIG. 5 is a top plan view thereof.

FIG. 6 is a bottom plan view thereof.

FIG. 7 is a front, right side and top perspective view thereof.

FIG. 8 is a rear, left side and bottom perspective view thereof.

FIG. 9 is a front, right side and top perspective view thereof in an environment in which it may be used; and,

FIG. 10 is a rear, left side and bottom perspective view thereof in an environment in which it may be used.

The broken lines in the figures show portions of the mounting assembly and environment that form no part of the claimed design.

1 Claim, 10 Drawing Sheets
